[57] CLAIM

The ornamental design for a foldable combination chair and table, as shown and described.

DESCRIPTION

FIG. 1 is a perspective view of a foldable combination chair and table showing my new design in the form of a chair as seen from a position above and to the right thereof;

FIG. 2 is a perspective view thereof showing same reformed into a table;

FIG. 3 is a perspective view thereof showing same in folded condition;

FIG. 4 is a top plan view thereof in the form of a chair;

FIG. 5 is a front elevation thereof in the form of a chair;

FIG. 6 is a left side elevation thereof in the form of a chair;

FIG. 7 is a rear elevation thereof in the form of a chair; and,

FIG. 8 is a bottom plan view thereof in the form of a chair.

The right side elevation is a mirror image of the left side.
